(57) **CLAIM**

The ornamental design for a charging handle for a firearm as shown and described.

DESCRIPTION

FIG. 1 is an elevated rear left-side perspective view of a charging handle for a firearm showing our new design.

FIG. 2 is an elevated rear right-side perspective view of the charging handle for a firearm of FIG. 1.

FIG. 3 is a depressed front right-side perspective view of the charging handle for a firearm of FIG. 1.

FIG. 4 is a rear elevational view of the charging handle for a firearm of FIG. 1.

FIG. 5 is a front elevational view of the charging handle for a firearm of FIG. 1.

FIG. 6 is a top plan view of the charging handle for a firearm of FIG. 1.

FIG. 7 is a bottom plan view of the charging handle for a firearm of FIG. 1.

FIG. 8 is a left-side elevational view of the charging handle for a firearm of FIG. 1; and,

FIG. 9 is a right-side elevational view of the charging handle for a firearm of FIG. 1.

The broken lines in the figures depict portions of the charging handle for a firearm that form no part of the claimed design. FIGS. 6 through 9 are presented at a reduced scale relative to FIGS. 1 through 5.
